UNITED STATES PATENT OFFICE.

FREDERICK TURNER, OF PHILADELPHIA, PENNSYLVANIA.

DESIGN FOR A BADGE OR PIN.

SPECIFICATION forming part of Design No. 16,667, dated April 27, 1886.

Application filed March 3, 1886. Serial No. 193,911. Term of patent 14 years

To all whom it may concern:

Be it known that I, FREDERICK TURNER, a citizen of the United States, residing at Philadelphia, in the county of Philadelphia and State of Pennsylvania, have invented and produced a new and original Design for a Badge or Pin, of which the following is a specification, reference being had to the accompanying drawings, in which—

Figure 1 is a perspective view of a pin bearing my design, and Fig. 2 is an edge view of the same.

The design consists of a pin having an annular base, with an ornamental circle, *a*, on its perimeter, a plain field within an ornamental square border, *b*, inside of the same,

and a triangular space, *C*, of a contrasting ground within the square.

Having described this design, what I claim is—

The design for a badge or pin herein shown and described, consisting of an annular base with an ornamental circle on its perimeter, a plain field within an ornamental square border inside the same, and a triangular space of a contrasting ground within the square.

In testimony whereof I affix my signature in presence of two witnesses.

FREDERICK TURNER.

Witnesses:

THOS. J. WALLACE,
HERM. W. GIESECKE.
